CHARLES T. RAY, OF LOUISVILLE, KENTUCKY, ASSIGNOR TO B. F. AVERY & SONS, OF LOUISVILLE, KENTUCKY, A CORPORATION OF KENTUCKY.

DISK PLOW.

1,311,773.

Specification of Letters Patent. Patented July 29, 1919.

Application filed August 15, 1916. Serial No. 115,018.

To all whom it may concern:

Be it known that I, CHARLES T. RAY, a citizen of the United States, residing at Louisville, in the county of Jefferson and 5 State of Kentucky, have invented new and useful improvements in Disk Plows, of which the following is a specification.

This invention has particular reference to improvements in mountings for the 10 table ground treating disks of tillage implements, especially of those implements whose disks are arranged to turn the soil,—plows, for example,—and embodies novel features of construction and combinations of 15 parts substantially as hereinafter described and particularly set forth in the appended claims.

One of the most important objects of the 20 invention is to provide a mounting which will enable the angle of inclination of the disk with respect to a plane perpendicular to the surface of the ground to be quickly changed and cause the disk to be held securely in its new position.

25 Another of the more important objects of the invention is to provide a disk bearing of simple and practicable construction which may be easily and readily put together and taken apart and in which the disk journal 30 will rotate with a minimum of friction.

These objects, and others, are secured in the construction illustrated in the accompanying drawings, wherein:

Figure 1 is a perspective view of a preferred embodiment of the invention, viewed from the rear.

Fig. 2 is a detail sectional view on a line vertically through the axis of the disk and disk carrier.

40 Similar characters of reference denote corresponding parts in both figures.

A disk plow has been selected to exemplify the invention, this being the preferred application thereof: A designates a part of the 45 frame, which may be of any suitable construction, B the concave-convex furrow turning disk such as is usually employed in plows of this type and C the scraper commonly used with such disks. These disks, particularly when employed in soil-turning implements,—as plows, for example,—are commonly set at an angle to the line of draft and it has been proposed to provide for their adjustment upon a vertical axis to take more or less land. The present invention is not

essentially concerned with any adjustment of the disk upon a vertical axis, but is essentially concerned with an adjustment of the disk upon an approximately horizontal axis to vary its pitch. In a soil-turning implement, as a plow, for example, the disk is so disposed that its outer peripheral edge is in a plane diagonal to the line of draft, as indicated by the drawing.

In this particular exemplification of the 65 invention the frame is provided with a member 10, suitably arranged to carry a support or standard 11, which depends therefrom at an appropriate angle. The support or standard 11 has a channeled portion 12 which receives the frame-member 10, the upper and lower lips 12^a at opposite sides of the channel in said portion 12 engaging the upper and lower surfaces of the frame member 10. It is also preferably formed with a longitudinal fin 13 and, as shown, is preferably secured to the frame-member 10 by through-bolts 14, 14 disposed on opposite side of the fin.

The disk B is secured to a backing 15 arranged at the axis thereof and this backing is provided with a rearwardly extending spindle 16, which forms the journal for the disk. This journal extends into a socket 17^a formed longitudinally in a disk carrier 17. 85 The carrier is also, preferably, formed to receive antifriction rollers 18, as hereinafter more particularly set forth.

The disk-carrier 17 is pivoted so that it may be moved upon an axis intermediate its 90 ends, the said axis being approximately horizontal and preferably substantially at right angles to the axis of rotation of the disk and preferably at an angle to the line of draft, to thereby change the position of the disk 95 with reference to a plane perpendicular to the surface of the ground without altering its angular relation to the line of draft, and is provided with means whereby this change in the position of the disk may be readily 100 accomplished and the disk fixedly secured in the new position, said means being preferably of such nature that the disk may be quickly moved to and effectively held in any one of a series of selected positions of adjustment around said axis.

In this exemplification of the invention the disk carrier is mounted upon an approximately horizontal pivot bolt 19, which is oblique with relation to the line of draft of 110

the implement and extends through an opening 17^b in the carrier and through corresponding openings in the lower end of the support 11, the support being preferably 5 bifurcated at 11^c and the carrier preferably having a lug 17^c to enter the bifurcated portion of the support, as shown.

The adjusting and securing means preferably employed consists of a member—as the 10 threaded rod 20, for example—whose lower end is pivoted—as by the pivot 20^a—to the rear end of the disk-carrier 17 and whose upper end is provided with means—as the nuts 21, 21, for example—by which it may 15 be secured in different positions with relation to an appropriate fixed part of the structure—the bracket 22 for example. In this exemplification of the invention, the bracket 22 is mounted on the side of the 20 frame member 10 opposite the channeled portion 12 of the support 11 and has an upper lip 22^a to engage the upper surface of said frame member, and is secured by the same bolts 14 which secure the support 11. The 25 bracket has a member 22^b through which the rod 20 extends. Owing to the peculiar angular disposition of the parts, this member 22^b is preferably arranged at an angle to the horizontal flange 22^c of the bracket. 30 The nuts 21, 21, engage the upper and lower surfaces of this member 22^b and it will be apparent that when the nuts are slackened the length of the rod between the member 22^b and the disk-carrier 17 may be increased 35 or diminished, thereby adjusting the carrier on its horizontal axis to change the pitch of the disk to suit the immediate requirement. By tightening the nuts the disk is effectively held in its new position.

40 It is preferred to arrange the rear end of the carrier at an upward inclination and to bifurcate it, as shown at 17^a to receive the lower end of the adjusting rod 20, and to dispose said rod in line with said upwardly 45 inclined end of the carrier, as shown.

In order that the disk B may rotate with a minimum of friction relatively to the carrier 17, the journal receiving socket 17^a of the latter has its inner wall spaced from the 50 inner end of the journal 16 and the face of the carrier is formed, around the socket, with a recess 23 which receives the balls 18 and the ball cage 18^a and whose inner wall sustains the end thrust. The space at the 55 inner end of the journal forms a pocket for lubricant, which lubricant is preferably supplied through an opening normally closed by the element 24, which may be either a grease cup or a plug; the former being preferred. The forward end of the carrier 17 is provided with a circular flange 25 and the 60 backing plate 15 is provided with a channel which is concentric with the journal 16 and receives said flange. In this particular exemplification of the invention, the channel 65

is formed by securing a separate member to the rear face of the backing plate proper, said member comprising portions 26 and 26^a offset from each other, the portion 26 receiving the flange of the carrier and the portion 26^a lying against the face of the backing plate and being secured thereto by suitable means, as the screw bolts 26^b, for example.

The support 11 is further provided with a longitudinally-channelled member, 27, 75 preferably formed integral therewith, which rises from the horizontally channelled portion 12 of the support and receives the lower end of a rod 28 which is suitably secured thereto, preferably by the bolt 29. This rod 80 serves as a support for the scraper C, which has a rod 31 extending through a vertical opening in a sleeve 30, the sleeve also having a member 30^a by which it is mounted on the rod 28. It will be noted that the sleeve is 85 adjustable longitudinally of the rod 28 and the rod 31 is adjustable longitudinally in the sleeve, whereby the position of the scraper may be regulated, suitable means, as the clamping bolt 32 being provided to hold the 90 rod 31 and a like clamping bolt (not shown) provided to fix the sleeve in its adjusted position on the rod 28.

It will be understood that in practice there may be a plurality of these disks 95 connected in the manner herein described with the frame of the implement.

Having now described the invention what I believe to be new and desire to secure by Letters Patent, is:—

1. In a tillage implement, the combination with a frame and a support, of a disk carrier pivoted intermediate its ends upon said support, a disk journaled at one end of said carrier, the opposite end of said carrier being upturned, a threaded rod pivoted at its lower end to said upturned end of the carrier, a bracket carried by the frame above the carrier, and nuts carried by the rod for binding the same against movement with respect to the bracket.

2. In a tillage implement, the combination of a frame, a support secured thereto, a disk carrier pivoted upon said support, the pivot of the carrier being disposed so that the carrier is fulcrumed upon a horizontal axis which is oblique to the line of draft of the implement, a soil working disk rotatably mounted on said carrier and means pivoted to that end of the carrier remote from the disk for rocking the carrier with relation to said support and upon said pivot and for securing the carrier in its changed positions about said pivot.

3. In a tillage implement, the combination of a frame, a support secured thereto, a disk carrier pivoted intermediate its ends with relation to said support, the pivot of the carrier being disposed so that the carrier is fulcrumed upon a horizontal axis which

is oblique to the line of draft of the implement, a soil working disk rotatably mounted on one end of said carrier and means connected to the other end of the carrier where-
5 by the latter may be adjusted about the pivot and held in adjusted position.

4. In a tillage implement, the combination with a frame, a support secured thereto, a disk carrier pivoted intermediate its
10 ends upon said support, the pivot of the carrier being disposed so that the carrier is fulcrumed upon a horizontal axis which is oblique to the line of draft of the implement, a soil working disk rotatably mounted
15 on one end of said carrier, an adjusting member connected to the opposite end of the carrier and means for fixing the adjusting member in adjusted position with relation to the frame.

20 5. In a tillage implement, the combination with a frame, a support secured thereto, a disk carrier pivoted intermediate its ends upon said support, the pivot of the carrier being disposed so that the carrier is fulcrumed upon a horizontal axis which is oblique to the line of draft of the implement, a soil working disk rotatably mounted
25 on one end of said carrier, a longitudinally adjustable member pivotally connected to the opposite end of the carrier, and means for holding said member in adjusted position with relation to the frame, said means comprising nuts threaded upon
30 said member.

35 6. In a tillage implement, the combination of a frame, a support secured thereto, a disk carrier pivoted intermediate its ends upon an approximately horizontal axis to said support, a soil working disk rotatably mounted upon the carrier at one side of the pivot, an adjusting element pivotally connected to the carrier at the other side of said pivot and provided with means for holding it in adjusted position with relation
40 to the frame.

45 7. In a tillage implement, the combination of a frame, a support carried by the frame, a disk carrier pivoted to the support upon an approximately horizontal axis, a soil working disk mounted upon the carrier, a threaded adjusting member for the disk carrier one end of which is pivotally connected with the carrier, a bracket carried by the frame through which the other
50 end of the adjusting member passes and nuts upon the adjusting member which engage above and below the said bracket and which serves to impart endwise adjustment to said member with respect to the bracket.

60 8. In a tillage implement, the combination of a frame member, a support having a channeled rear face on one side of said frame member, a bracket having a channeled rear face on the other side of said
65 frame member, means for securing the sup-

port and bracket to the frame member, a disk carrier pivoted upon an approximately horizontal axis to the support, a disk rotatably mounted upon one end of the disk carrier and an adjusting means between the opposite end of the disk carrier and the bracket.

70 9. In a tillage implement, a carrier having at one end a means by which a soil working disk may be rotatably supported by the carrier, the carrier also having intermediate its ends a means by which it may be pivotally connected to a support to be adjustable upon an approximately horizontal axis with relation to the support, and having its end opposite the disk provided with means for swinging it about said axis to change the pitch of the disk.

75 10. In a tillage implement, a carrier for a disk, said carrier having intermediate its ends a means by which it may be pivotally connected to a support to be adjustable upon an approximately horizontal axis with relation to the support and having one of its ends provided with means for swinging it about said axis to change the pitch of the
80 disk and having at its opposite end an element of an anti-friction bearing.

85 11. In a tillage implement, a carrier for a disk, said carrier having a longitudinal bore and having intermediate its ends an ear by which it may be pivotally connected to a support, and having one of its ends constructed for pivotal engagement with an adjusting element, and an element of an anti-friction bearing at its opposite end.

90 12. In a tillage implement, a carrier for a disk, said carrier having a longitudinal bore and having intermediate its ends an ear by which it may be pivotally connected to a support, and having one of its ends constructed for pivotal engagement with an adjusting element, and a lateral flange at its opposite end.

95 13. In a tillage implement, a carrier for a disk, said carrier having intermediate its end a means by which it may be pivotally connected to a support, and having one of its ends provided with an element for adjusting it about its pivot, the opposite end of the carrier being expanded and provided with an axial bore to receive the journal of the disk, and having a recess concentric with the bore to receive anti-friction elements and a flange concentric with the recess to engage the backing of the disk.

100 14. In a tillage implement, a disk and its shaft, a carrier having a longitudinal bore to receive the disk-shaft, said shaft and bore being relatively of such length that a space will be provided between the inner end of the shaft and the corresponding end of the bore, friction reducing bearing members between the outer end of the carrier and the contiguous part of the disk, correlated to sustain the end thrust and keep the inner
105 130

end of the shaft out of engagement with the inner end of the bore, said carrier also having means through which lubricant may be supplied to said space, and further having, 5 intermediate its ends, a means by which it may be pivotally connected to a support to be adjustable upon an approximately horizon-

tal axis with relation to the support and its end opposite the disk provided with means for swinging it about said axis to change 10 the pitch of the disk.

In testimony whereof I have hereunto set my hand.

CHARLES T. RAY.
